UNITED STATES PATENT OFFICE.

CHARLES E. HEINZE, OF NEWARK, NEW JERSEY.

BRIDLE-BIT.

SPECIFICATION forming part of Letters Patent No. 326,648, dated September 22, 1885.

Application filed January 2, 1885. (No model.)

To all whom it may concern:

Be it known that I, CHARLES E. HEINZE, a citizen of the United States, residing in Newark, Essex county, New Jersey, have invented 5 certain new and useful Improvements in Bridle-Bit Mouth-Pieces, fully described and represented in the following specification, and the accompanying drawings, forming a part of the same.

10 This invention consists in a bridle mouth-piece formed of a bundle of flexible wires secured in suitable heads, so that the cheeks may be attached thereto, and the wires are shown herein as twisted into a wire rope, so as to secure a greater degree of flexibility, as it is well known that a bundle of parallel straight wires or fibers is not easily bent, on account of the extension upon one side of the bundle and the compression at the opposite side. 15 In the annexed drawings, Figure 1 is a longitudinal section of a mouth-piece transverse to the rings, the wire rope not being shown in section, and the ends being shown as soldered into sockets formed in the heads. Fig. 2 is a 20 view of the mouth-piece and rings, with the ends of the rope and its sockets shown in section, the manner of fastening the rope at each end being described hereinafter.

25 A is the rope; B, the heads at each end of the rope, into which the rings C are fastened in any ordinary manner; and D, D', and D'' are sockets attached to the heads for securing the ends of the rope thereto. Three different methods are shown in the drawings for fastening the rope in the sockets, Fig. 1 showing 30 parallel sockets D integral with the heads B, and having the ends of the rope secured by solder. In such construction the ends of the rope and the interior of sockets are tinned 35 in the ordinary manner, and then sweated together by heat, as is common.

40 In Fig. 2 the sockets are removable or made apart from the heads and secured thereto, a threaded plug, B', being formed upon the side of the head and fitted to the outer ends of the sockets. The opening at such outer end is made larger than that at the inner end of the socket, the socket being thus enlarged internally to permit the expansion or fastening 45 of the rope therein. Such expansion may be effected, as shown in the section at the left

end of Fig. 2, by making the socket D' conical internally and driving a tapering pin, E, into the center of the rope, or by recessing the socket D'' with a shoulder, F, and riveting 55 or bending the wires at the end of the rope over upon such shoulder, as shown at the right-hand end in Fig. 2.

The rope is distinctly shown in the drawings as formed of separate strands made of 6c fine wires twisted together, and the ends are thus easily expanded in the manner described, and when secured in the sockets become firmly attached to the heads B, while the intermediate part at A retains the desired degree of 65 flexibility. In place of the pin E, melted metal may be poured in the central opening of the expanded rope, as is indicated by the dark spot at G, at the right-hand end of Fig. 2.

The state of the art in such inventions is indicated in United States Patents Nos. 56,872, 70 56,923, and 69,079, the latter showing large wires twisted together, but in such manner as to form a "stiff mouth," as claimed therein. Wires have also been twisted so as to form 75 hinges or joints, and thus form a flexible mouth; but in such cases the strength I secure is unattainable, as the entire construction is no stronger than the separate links. My improvement also differs from these in the facility with which the ends of the bundle of wires can be secured in the heads, their flexibility enabling me to bend or wedge them in the manner shown above, for securing them in the 80 sockets, and thus removing and renewing them 85 when worn.

I am also aware that a mouth-piece with cheeks has been made by twisting two wires or rods together, and I do not, therefore, claim the mere twisted wires in my construction, but the rope formed of separate strands which are individually composed of several 90 distinct wires. It will therefore be seen that the flexibility of my mouth-piece is dependent upon the use of fine wires and upon their being formed into separate twisted strands 95 united into a rope, as such construction is much more flexible than any other. I have, however, claimed my invention as a bundle of fine flexible wires to distinguish it from the 10 rigid twisted wires heretofore used, but not combined into strands.

In Fig. 1 a rubber covering, R, is shown, which may be stretched over the surface of the rope to protect the horse's mouth, if required, from the roughness of the rope. Such covering may be used, if desired, although I make no claim to the same, as it has long been used for a similar purpose.

It is obvious that the sockets D' and D² are removable from the heads B, and in case the strands or wires of the rope A become worn the rope may be removed from the sockets by unfastening its ends, and a new piece substituted without any change in other parts of the bit.

Having thus described my invention, I claim the mouth formed of the wire rope in the following manner:

1. In a flexible mouth-piece for a bridle-bit, the combination, with suitable end pieces or heads, of the intermediate bundle of fine flexible wires twisted into strands and united into

a flexible rope and secured in the heads, substantially as herein described.

2. In a mouth-piece for a bridle-bit, the combination, with the heads B, of the removable sockets having the wire rope fastened therein, substantially as shown and described.

3. The combination, with the heads B, provided with the threaded plugs B', of the sockets provided with an external aperture to fit the wire rope and expanded internally with the ends of the wire rope A, expanded within them, and the sockets screwed to the plugs B', as and for the purpose set forth.

In testimony whereof I have hereunto set my hand in the presence of two subscribing witnesses.

CHARLES E. HEINZE.
